Fig. 1.

Fig. 2.

Fig. 3.

Fig. 4.

Fig. 5.

Fig. 6.

Fig. 7.

FIG. 1 is a top plan view of a transparent cuvette, for dividing and photometrically analyzing equal quantities of a liquid, showing our new design;

FIG. 2 is a front view in elevation of the design shown in FIG. 1;

FIG. 3 is a bottom plan view of the design shown in FIGS. 1 and 2;

FIG. 4 is a rear view in elevation of the design shown in FIGS. 1-3;

FIG. 5 is a left end view of the design shown in FIGS. 1-3;

FIG. 6 is a right end view of the design shown in FIGS. 1-3; and

FIG. 7 is a cross-sectional view taken through FIG. 2 along the line 7—7.

We claim:

The ornamental design for a transparent cuvette for dividing, and photometrically analyzing equal quantities of liquid, as shown and described.
